(57) **CLAIM**

The ornamental design for a desktop charger/desktop stand, thereof, as shown and described.

DESCRIPTION

FIG. 1 is a perspective top-front view showing my new design;

FIG. 2 is a top view thereof; and,

FIG. 3 is a perspective top-rear view in an open position thereof.

The unshown regions of the desktop charger/desktop stand form no part of the claimed design. The broken line showing of the connector interfacing regions is for illustrative purposes only and forms no part of the claimed design.

1 Claim, 2 Drawing Sheets

FIG. 1

FIG. 2

FIG. 3
